GAME APPARATUS

Carl M. Peshal, Milwaukee, Wis., assignor of one-half to Bolus S. Wisniewski, Milwaukee, Wis.

Application August 19, 1940, Serial No. 353,261

1 Claim. (Cl. 273—144)

This invention appertains to games and game apparatus, and more particularly to a counter selector and delivering device.

One of the primary objects of my invention is the provision of a novel apparatus for selecting numbered balls or other counters, one at a time, by chance from a group of such counters, the device being particularly susceptible for use in games of the type played by a large assemblage of persons and commonly known to the public as "Bingo."

Another object of my invention is to provide means actuated by the operator of the device for agitating and mixing the group of counters each time a single counter is selected therefrom, whereby to prevent the predetermined selection of certain counters.

Another salient object of my invention is to provide a counter table forming a part of the device properly numbered to agree with the numbers on the counters for receiving the counters as selected, whereby the selected counters will be in view of the players.

A further object of my invention is to provide manual means for simultaneously releasing all of the counters selected from the table after the completion of a game for permitting the return of such counters to the group of counters in the body portion of the device, so that the device will be instantly ready for the replaying of another game.

A further important object of my invention is to provide a large indicating board in full view of and clearly visible to all of the players, the board having numbers or the like corresponding to the numbers or markings on the counters and table, with electric lamps for selectively illuminating said numbers, and means for automatically closing circuits through the lamps as the selected counters are placed upon the table to visually indicate to the players the number of each counter as selected.

A still further object of my invention is to provide means on the table automatically operated from the counter release device for indicating to the operator of the machine the number of games played.

A still further object of my invention is to provide means for indicating on the display board the number of games played automatically operated from the means on the machine for indicating to the operator the number of games played.

With these and other objects in view, the invention consists in the novel construction, ar-

rangement, and formation of parts, as will be hereinafter more specifically described, claimed, and illustrated in the accompanying drawings, in which drawings:

5 Figure 1 is a top plan view of my improved device, with parts thereof broken away and in section to illustrate structural detail.

Figure 2 is a longitudinal sectional view through the machine, taken on the line 2—2 of Figure 1, looking in the direction of the arrows, and showing one end of the agitator and selector board in its raised position for delivering a single counter to the operator.

Figure 3 is a transverse sectional view through the machine, taken on the line 3—3 of Figure 1, looking in the direction of the arrows, and illustrating the mechanism for releasing the counters after the playing of a game.

15 Figure 3—A is a fragmentary sectional view similar to Figure 3 and showing the counter release mechanism in its actuated position for permitting the simultaneous return of the selected counters to the group of counters in the body of the machine.

Figure 4 is a detail, transverse sectional view taken on the line 4—4 of Figure 2, looking in the direction of the arrows, showing the counter selector in its raised position for delivering a counter to the operator.

20 Figure 5 is a view similar to Figure 4, but showing the counter selector in its lowered position for receiving a counter from the counter agitating board.

25 Figure 6 is an enlarged, fragmentary, horizontal, sectional view taken on the line 6—6 of Figure 5, looking in the direction of the arrows, showing the counter selector.

Figure 7 is a fragmentary, detail, plan view showing the normal position of the counter release plate and the operating stud for the game indicating pointer.

30 Figure 8 is a view similar to Figure 7, showing the operated position of the counter release plate and the movement of the stud by said plate.

Figure 9 is a view similar to Figure 8 and showing the release plate moved back to its normal position, with the stud for the game indicating pointer advanced one notch or step by said plate.

35 Figure 10 is an enlarged, detail, fragmentary, sectional view taken on the line 10—10 of Figure 1, looking in the direction of the arrows, illustrating the game indicating pointer.

40 Figure 11 is a view illustrating the wiring diagram for the indicating board and the operator's device.

Referring to the drawings in detail, wherein similar reference characters designate corresponding parts throughout the several views, the letter A generally indicates my novel game apparatus, and the same is in the nature of a rectangular box or receptacle, and, hence, the same includes a bottom wall 15, end walls 16 and 17, and longitudinally extending side walls 18 and 19. This body portion of the apparatus can be provided with suitable feet 20 for resting upon a suitable surface, and the top of the body is closed by a removable table or cover plate 21. This cover plate has formed therein a series of longitudinally extending rows of equidistantly spaced openings 22 into which are adapted to be placed counters 23 selected from a group of counters in the body portion, as will be hereinafter more fully described. The counters are of such a size as to freely pass through the openings.

As the counters are selected and placed in the openings, the same are held against falling through the openings by a slidably release plate 24. The counter release plate 24 is provided with longitudinally extending slots 25. The side edges of the release plate are slidably received in supporting guide tracks 26, which extend transversely of the body, and these tracks can be secured in position in any preferred manner. As illustrated, the ends of the tracks are secured by fastening elements 27 to corner posts 28 forming a part of the body of the box or receptacle.

In the normal position of the release plate, the slots 25 are disposed out of registration with the openings 22, and, hence, the counters, as selected, rest upon the release plate. When the release plate is shifted, the slots 25 can be brought below the openings 22 for permitting the simultaneous release of all of the selected balls into the body of the box.

In one form of my game device, the balls or counters can be consecutively numbered, and, in this instance, the playing table 21 is provided adjacent the openings 22 with consecutive numbers, and as a counter is selected, the number thereof is announced and this counter is placed in the opening having a corresponding number.

The means for actuating the release plate 24 can consist of an operating plunger 29, and this plunger extends through the side wall 19 and is provided with an operating hand grip 30. The rear end of the plunger is secured to a depending angle bracket 31 firmly fastened to the lower face of the release plate. In order to normally hold the release plate 24 in its ball or counter supporting position, the plunger 29 has coiled thereabout an expansion spring 32. This spring is confined between the angle bracket 31 and the inner face of the wall 19.

One of the important features of my invention is the provision of novel means for agitating and mixing the counters in the body and for selecting and delivering one of the counters by chance to the operator of the machine. This means includes a rocking, agitating board 33, and this board is secured intermediate its ends, as at 34, to a transversely extending rock shaft 35. The shaft 35 is rockably mounted in the side walls 18 and 19, and one end of the shaft protrudes through the wall 19 and has secured thereto an operating lever 36. The group of counters rests upon the selector board, and, obviously, by operating the lever 36, the board can be rocked back and forth for agitating and mixing the counters.

One end of the board 33 terminates short of the end wall 17 of the body or casing, and this

end of the board has connected therewith a ball or counter receiving trough 37. Arranged within the body or casing adjacent the side wall 17 and in front of the agitating and selector board 33 is disposed a shield 38 for preventing the balls from running off the board as the board is rocked back and forth. The upper end of the shield carries a counter guide channel 39 which, in effect, forms a continuation of the trough 37, and when the end of the board 33 carrying the trough is elevated, the trough is in longitudinal alignment with the channel, and both the trough 37 and the channel 39 incline downwardly toward a rigid vertically disposed guide tube 40.

15 This guide tube 40 extends from the bottom wall 15 of the body or casing to and through the table or cover plate 21, and the guide tube is provided with an opening 41 into which the channel 39 extends, so that the balls or counters can roll freely into the guide sleeve.

20 Freely mounted within the guide sleeve is the ball selector and elevator member 42. This member is of cylindrical construction, and when the same is in its lowered position, the opening 41 is uncovered thereby and a counter can roll into the guide tube 40 and on the upper end of the cylindrical member 42. When the cylindrical selector member 42 is elevated, its body portion closes the opening 41 for preventing the further 25 admittance of the counters into the guide sleeve, and the selector member, during its upward movement, will carry a selected ball above the table top 21 and in view of the players. The operator can then remove the ball from the selector member and place the same in the proper numbered opening.

25 In accordance with my invention, the counter selector member 42 is operated with the agitating board 33, and, consequently, the counter selector member 42 adjacent its lower end carries the laterally extending ring 43, which loosely encircles a stud or bolt 44 carried by an arm 45 rigidly secured to the adjacent end of the agitating board 33. If preferred, rubber or similar pads 46 30 can be placed about the stud or bolt 44 to eliminate shock and reduce noise incident to the operation of the machine.

35 From the description so far, it can be seen that each time the lever 36 is pressed down, the agitator board 33 carrying the trough 37 and the selector member 42 will be depressed, and a counter will roll into the guide tube 40 and on top of the selector member. Upon the return of the lever 36 to its raised position, the agitator board 33 will be rocked in the opposite direction, and the trough 37 and the selector member 40 will be elevated, and a counter will be raised above the playing table 21.

40 In order to normally hold the group of counters in a lowered position away from the trough 37 and the lever 36 in a raised position, one of the fastening bolts 34 employed for connecting the agitating board 33 to the rock shaft 35 is extended a considerable distance below the rock shaft, and this bolt has connected thereto a contractile coil spring 47. The other end of the coil spring 47 is suitably anchored, as at 48, to the casing or body. The bottom wall 15 can be provided with sponge rubber bumper pads 49 adjacent the opposite ends of the agitator board, so as to reduce shock and noise incident to the operation of the board.

45 In playing games of the "Bingo" type, it is important to keep track of the number of games

played, both from the standpoint of the operator and players.

In order that the operator will have a positive means for keeping track of the games played, a game number indicating pointer 50 is provided. This pointer 50 is rigidly secured to a stud 51, and the stud is mounted for sliding movement longitudinally of the playing table 21 in a guide slot 52. The stud 51 extends through the slot and into the body or casing, and also through the ball or counter release plate 24. At equidistantly spaced points along the slot 52, the playing table is consecutively numbered, and the pointer 50 is adapted to move along the slot from one number to the other, and these numbers indicated by the reference characters 53 indicate the number of games being played.

To prevent error and mistakes in operating the game number indicating pointer 50, I have provided means for automatically actuating the pointer the distance between the numbers 53 on each operation of the ball release plate 24. This means includes a longitudinally extending slot 54 formed in the ball or counter release plate 24, and each longitudinal edge of the slot 54 is provided with a row of ratchet teeth 55 and 56. The teeth of the row of ratchet teeth 56 are out of alignment with the teeth of the row of ratchet teeth 55, and said teeth 56 lie between the teeth 55.

The operation of the pointer 50 is as follows (see Figures 7, 8, and 9). During the playing of the first game, the pointer 50 lies at the extreme lefthand end of the slot and over the number "1" of the game indicating numbers 53. After the game has been played and the balls are to be released, the hand grip 30 is pulled outwardly, carrying the ball release plate 24 forwardly to permit the dropping of the balls onto the agitator board 33. As the release plate 24 moves forwardly, the stud 51 of the pointer 50 engages the inclined face of the first ratchet tooth 56, and the stud is slid in its slot 52 to the right, as shown in Figure 8.

Upon the release of the handle 30 and the return of the release plate 24 by the spring 29, the stud 51 will engage the inclined face of the adjacent ratchet tooth 55, and this face will continue the sliding movement of the stud in the slot 52, as shown in Figure 9. The teeth 56 and 55 are so arranged that upon each movement of the release plate, the pointer will travel from one number to the other of the row of numbers 53.

In some clubs where the game is played daily or weekly by a great number of persons, it is advisable to provide a large indicating board in the room for indicating visually to the players the numbers of the counters as the same are selected.

In connection with my novel apparatus A, I can provide means for automatically and electrically operating such a board. As illustrated in Figure 11, an indicating board 60 can be provided, and this board can have translucent inserts 61 therein, and these inserts can be consecutively numbered to correspond to the numbers on the counters and the numbers for the ball openings in the apparatus.

The numbers on the translucent plate 61 are adapted to be illuminated by lamps 62, and the circuits through these lamps can be automatically closed by a counter as the counter is played in the correct opening 22 on the table top and on top of the release board 24. To carry

out this feature, the release board 24 can be formed from electric insulating material, and the upper face of the board adjacent each slot 25 can be provided with a series of electric conducting strips 63. Arranged alongside each strip 63 and in spaced relation thereto are independent short contact strips 64, and there is a short contact strip 64 for each ball opening in the table top.

10 In the normal position of the release board 24 the contact strips 63 and the short contacts 64 are disposed below the ball openings, and when a ball is played in an opening, the same is adapted to rest upon one of the short contacts 64 and on 15 one of the strips 63, so as to bridge these contacts.

The long contact strips 63 are connected together by bus wires 65, and one of the strips is then connected by wires 66 and 67 to one terminal of a battery 68 or other source of electrical energy. The short contacts 64 are each connected by separate wires 69 to one terminal of its proper indicating lamp 62, and the other terminals of all of the indicating lamps 62 are 25 grounded to a common lead wire 70 leading to the other terminal of the battery 68 of the other source of electrical energy.

From the above, it is to be understood that there is a short contact 64 for each indicating 30 lamp, and the contact strip, for instance, for the ball opening number "1" is connected with the indicating lamp placed in rear of the translucent panel 61 on the scoreboard bearing the corresponding indicia number "1."

35 Thus, upon the selecting of a ball or counter and the placing thereof in its proper numbered opening, the ball being formed of electric conducting material will close a circuit through its proper indicating lamp on the indicating board.

40 It will also be advisable to provide visual means for indicating to the players the number of the game being played, and, consequently, I arrange in rear of each numbered translucent panel 61 a colored indicating lamp 71. The circuits through the colored indicating lamps 71 are 45 controlled by the position of the pointer 50. Consequently, I mount below the release board 24 a longitudinally extending contact carrying insulating panel 72.

50 The ends of this panel 72 can be suitably secured to the corner posts 28. The panel 72 has connected thereto a longitudinally extending continuous contact strip 73, and this strip is disposed on one side of a longitudinally extending slot 74 formed in the panel 72. The slot 74 is in vertical alignment with the slot 52 in the table, and the stud 51 for the game pointer extends through said slot 74.

On the other side of the slot 74 from the 60 continuous contact strip 73 is provided a plurality of equidistantly spaced short contacts 75. There is a contact 75 for each one of the game indicating numbers 53, and the stud 51 carries an electrical conducting bridge-piece 76 for traveling movement over the continuous contact strips 73 and from one short contact 75 to the other.

In order to maintain a desired contact between the bridge-piece 76 and the contact strip 73 and the contacts 75, the stud 51 has its lower end provided with an abutment 77. A spring 78 is coiled about the stud and engages the abutment and the lower face of the panel 72. Consequently, the spring pulls down on the stud and urges the bridge-piece into engagement with the contact.

To permit the closing of the circuits through the desired game indicating color lamps 71, the continuous bridge strip 73 has connected therewith an electrical conducting wire 79, which leads to and is electrically connected with the wire 67, which leads to the source of electrical energy. A separate electric conducting wire 80 is connected to each short contact 75, and these wires lead to one terminal of the correct colored game indicating lamp 71; that is, the wire 80, which is connected with the short contact 75 under the number "1" of the game indicating numbers 53 leads to the game indicating lamp 71 in rear of the translucent panel bearing the indicating number "1." The other terminals of the colored game indicating lamps 71 are also connected to a common return wire 81, and this wire is, in turn, connected to the wire 70, which leads back to the source of electrical energy.

From the description so far it can be seen that as the stud 51 for the pointer 59 is automatically actuated by the movement of the release panel 24, the bridge-piece 76 carried by the stud will be moved from one contact 75 to the other.

When the desired number of games have been played, the release plate 24 is pushed partially in until the stud 51 lies between the rack bars 55 and 56, after which the operator grasps the pointer 50 and slides the same manually to the left to the number "1" game position. Upon release of the plate 24, the apparatus is ready for the playing of a new group of games.

The body or casing can be made from any desired materials and suitably treated to enhance the appearance thereof. The end walls 16 and 17 can be provided with handles 85 to facilitate the moving of the apparatus from place to place. If preferred, the wall 18, which faces the players can be formed from glass or other transparent material, so that the players can see the counters being moved back and forth during the operation of the machine.

It is also to be understood that the machine can be made in any size and that small inexpensive game devices can be manufactured, embodying the principles of my invention for home use. 5 Also, large machines of an ornamental character embodying the principles of my invention can also be made, and, if preferred, these large machines can be coin-controlled; that is, some conventional means can be provided for preventing 10 the operation of the machine until a coin of a suitable denomination has been deposited.

From the foregoing description it can be seen that the machines can be constructed either with or without the electrical signal appliance.

15 Changes in details may be made without departing from the spirit or the scope of my invention, but what I claim as new is:

In a game apparatus, a hollow body, an agitating board rockably mounted in said body for 20 supporting a group of counters, manual means for rocking the board to shift the counters back and forth, means for selecting one counter at a time from the group of counters and for delivering the selected counter exteriorly of the box up- 25 on each movement of the board, said means including an inclined trough on one end of the board for receiving counters, a stationary guard having a channel for receiving counters from the trough when the end of the board carrying the 30 trough is in a raised position, a vertically disposed guide sleeve extending through the table having a counter receiving opening in alignment with the channel, and a cylindrical counter receiving member slidably mounted in the guide 35 normally closing said opening and adapted to extend below the opening for receiving a counter when the end of the board carrying the trough is in a depressed condition, and means for operatively connecting the cylindrical counter selector 40 member with the board.

CARL M. PESHAL.
